WAVE GUIDE MODE TRANSFORMER

Roger E. Clapp, East Cambridge, Mass., assignor,
by mesne assignments, to the United States of
America as represented by the Secretary of War

Application August 1, 1945, Serial No. 608,316

5 Claims. (Cl. 178—44)

1

This invention relates to electrical apparatus and more particularly to apparatus for transmitting electrical energy.

It is well known in the art that electrical energy may be transmitted through a wave guide in several different modes or configurations of the electric and magnetic field. It is also known that the efficiency of transmission of the electrical energy is different for the different modes. It is often the case, however, that the most efficient mode is difficult to excite without exciting other undesirable modes within the wave guide. The expedient usually resorted to in eliminating these undesired modes is to excite the dominant mode in a wave guide that is small enough to eliminate all higher modes. A "mode transformer" is then employed to change from the dominant mode to the desired mode.

It is an object of the present invention, therefore, to present a novel mode transformer so designed that all undesirable modes are eliminated.

For a better understanding of the invention, together with other and further objects thereof, reference is had to the following description taken in connection with the accompanying drawings in which:

Fig. 1 is an isometric view of the invention;

Figs. 2 to 17, inclusive, are a series of sectional views of the device shown in Fig. 1 taken perpendicular to the main axis of the mode transformer at the lines 2—2 to 17—17 respectively;

Fig. 18 is a view of the method of transition from a cross shaped wave guide to a circular wave guide employed in Fig. 1;

Fig. 19 illustrates a second method of making a transition from a cross to a circular wave guide;

Fig. 20 shows a third method of making the transition from a wave guide in the shape of a cross to a circular wave guide;

Fig. 21 shows a rectangular wave guide excited in the dominant or the $TE_{0,1}$ rectangular mode;

Fig. 22 shows a circular wave guide excited in the $TE_{0,1}$ circular mode; and

Fig. 23 shows a circular wave guide excited in the $TE_{2,1}$ mode.

The present invention is designed to transform energy from the $TE_{0,1}$ mode in a rectangular wave guide to the $TE_{0,1}$ mode in a circular wave guide without setting up the $TE_{2,1}$ mode or any other undesired mode in the circular wave guide. The $TE_{0,1}$ rectangular mode is the dominant mode in a rectangular wave guide and the $TE_{0,1}$ circular mode is a mode which has very low attenuation characteristics. The undesirable $TE_{2,1}$

2

mode may be propagated in a circular wave guide that will propagate the $TE_{0,1}$ circular mode.

The mode transformer shown in Fig. 1 consists of seven transition sections in series so that a gradual transition is made from a rectangular wave guide 10 to a circular wave guide 12.

In the first transition section included between the lines 2—2 and 4—4 of Fig. 1 the shorter dimension of the rectangular wave guide 10 is gradually increased until it is twice its original length. A dividing section 14 is gradually introduced into the wave guide as shown in Fig. 3 until in Fig. 4 the single wave guide 10 in Fig. 2 has been divided into two identical wave guides 16 and 18 in Fig. 4. The second transition section is included between the lines 4—4 and 6—6. In this transition section the longer axes of both wave guides 16 and 18 are gradually rotated through 90° until the two wave guides are in the position shown in Fig. 6. The third transition section is very similar to the first transition section. It could be made up of two of the first transition sections placed side by side so that the two wave guides 16 and 18 at lines 6—6 are gradually changed to form four wave guides 20, 21, 22 and 23 as shown at line 8—8. In the transition section included between the lines 8—8 and 10—10 the longer axes of the four wave guides 20 to 23 inclusive are gradually rotated from the position shown in Fig. 8 through 45° until they are in a position shown in Fig. 10. At line 10—10 a hollow square 26 (see Fig. 10) is formed by the shorter sides of the four wave guides where they join. The fifth transition consists of gradually deforming the sides of the wave guide that form this square until at line 12 the space between the wave guides is entirely eliminated as shown in Fig. 12. In a transition made from line 12—12 to line 14—14 the dividing walls 28 between the four wave guides are gradually removed until at line 14—14 the transformer has the shape of a hollow cross as illustrated by Fig. 14. The final transition from the shape of the hollow cross is made as shown in Figs. 15 and 16 until at line 17—17 the circular shape is obtained. The transition between lines 14—14 and 17—17 is more clearly shown in Fig. 18. The solid line 30 in Fig. 18 represents the cross-section of the wave guide of Fig. 1 in the vicinity of line 14—14. The dotted lines 32 represent successive cross-sections of the wave guide going from line 14—14 to line 17—17. Only two quadrants of the transition are shown. It can be seen from Fig. 18 that the sides 34, 36, 38 and 40 of the transformer are moved gradually outward parallel to themselves until the circular

shape is obtained. A second form of transition that might be employed to go from the cross shape to the circular wave guide is shown in Fig. 19. In this type of transition the adjacent sides 42 and 44, and 46 and 48 of the transformer are gradually bent outward as indicated by the dotted lines 50 until the circular shape is obtained. The third type of transition illustrated in Fig. 20 is to expand the dimension of each of the four ends of the cross while maintaining the dimensions at the center of the cross constant until a circular wave guide divided into four quadrants by a thin dividing wall is obtained as illustrated by the single dotted line 52 in the two quadrants of Fig. 20. These dividing walls 52 are gradually reduced until the circular shape is obtained. If this third type of transition is used, the elimination of the dividing section 28 shown in Fig. 12 may be combined with this transition, thus shortening the length of this mode transformer.

The operation of this mode transformer is clearly illustrated by the arrows shown in the various cross-sections. These arrows represent direction of the electric field vector at some instance. No attempt has been made to show the relative phase between the vectors at successive cross-sections, because this phase relationship does not enter into the operation of the invention. It should be noted that the distance to the cross-section at line 2-2 from all points in any other cross-section is substantially the same so that no phase shift between the vectors in any cross-section is produced by different electrical lengths that the energy must travel.

Figs. 2 to 4 illustrate how the electric field represented by the single arrow at line 2-2 is gradually divided into two fields in phase at line 4-4. These two fields are then changed until they are 180° out of phase in space at line 6-6 while they are still in phase in time. At line 8-8 the original field has been split up into four fields. Two of these fields are in phase with the original field and two are 180° space degrees out of phase with the original field. At line 8-8 the four fields have been rotated so that each field is 90° out of phase in space to the field in the adjacent wave guides. The arrows in Figs. 15, 16, and 17 show how the four fields at line 14-14 are gradually shaped into the circular electric field at line 17-17. It can be seen that the change in the electric field from line 14-14 to line 17-17 will be essentially the same regardless of the type of transition used.

It can be seen from the above description that this transformer changes the electrical energy from the TE_{0,1} rectangular mode to the TE_{0,1} circular mode by properly dividing energy into various paths, changing the phase of this energy in space and then gradually recombining the energy in a single wave guide so that the desired mode is obtained. For the best operation of this transformer each succeeding transition section should be matched to the preceding section. This may be done by properly choosing the dimensions of the transformer or by introducing suitable impedance transformers between the sections. It should be noted that the various transition sections may be connected together with straight sections of rectangular wave guide if desired, but in general the shorter the physical length of the transformer the less the signal will be attenuated in passing through it.

This mode transformer may also be used to transform energy from the TE_{0,1} circular mode to the TE_{0,1} rectangular mode. In this case the

5
10
15
20

electric field configuration within each cross-section will be substantially the same as that shown in the drawings except that they will occur in reverse order. Advantages of this device may be summarized as follows. The TE_{0,1} rectangular mode is transformed to the TE_{0,1} circular mode with a minimum of interference from other modes. This device employs no mode filters so any loss from such devices is thereby eliminated. The device is bilateral, and, therefore, may be used to transform energy traveling in either direction from a circular to a rectangular wave guide; and the device may be constructed in sections, if desired, to facilitate the manufacture of the mode transformer.

While there has been described what is at present considered the preferred embodiment of the invention, it will be obvious to those skilled in the art that various changes and modifications may be made therein without departing from the invention.

What is claimed is:

1. A mode transformer comprising at least six serially connected transition sections, the first of said transition sections providing means whereby one wave guide may be connected to two similar wave guides, a second of said transition sections providing means whereby the axes of two wave guides may be rotated 90° in space, the third of said transition sections providing means whereby two similar wave guides may be connected to four other similar wave guides, the fourth of said transition sections providing means whereby the axes of four wave guides may be rotated through 45° in space, the fifth of said transition sections providing means whereby four wave guides may be connected to a single wave guide having the form of a cross, and the sixth of said transition sections providing means whereby a wave guide in a form of a cross may be connected to a circular wave guide.

2. A method of changing the mode of transmission of electrical energy from the TE_{0,1} rectangular mode to the TE_{0,1} circular mode including the steps of exciting a rectangular wave guide in the TE_{0,1} mode, dividing the electrical energy in said wave guide into two paths, rotating the configuration of the electrical field vectors in each of said paths through 90 degrees in space, dividing the electrical energy in each of said paths into two other paths, rotating the configuration of the electrical field vectors in the four paths thus formed through 45 degrees in space, and combining the energy from said four last-mentioned paths into a circular wave guide whereby the TE_{0,1} mode is excited in the circular wave guide.

3. A method of changing the mode of transmission of electrical energy from the TE_{0,1} rectangular mode to the TE_{0,1} circular mode including the steps of exciting a rectangular wave guide in the TE_{0,1} mode, dividing the electrical energy equally into n paths, rotating in space the electric field configuration in the first path by

55
60
65
70

$\frac{360}{n}$ degrees, rotating in space the electric field configuration in the second path by

75

$2\left(\frac{360}{n}\right)$ degrees, rotating in space the electric field configuration in the r th path by an amount

80

$r\left(\frac{360}{n}\right)$

where r includes all integers from 3 to n both inclusive, and recombining the energy in said n paths in a circular waveguide.

4. In a waveguide transmission system including a rectangular waveguide and a circular waveguide, a mode transformer comprising at least six transition sections, the first of said sections providing means whereby one rectangular waveguide may be connected to two similar waveguides, means joining a first end of said first section to said rectangular waveguide, the second of said sections providing means whereby the axis of two rectangular waveguides may be rotated 90° in space, means joining a first end of said second section to the second end of said first section, the third of said sections providing means whereby two rectangular waveguides may be connected to four similar waveguides, means joining a second end of said second section to a first end of said third section, the fourth of said sections providing means whereby the axes of four waveguides may be rotated through 45° in space, means joining a first end of said fourth section to a second end of said third section, the fifth of said sections providing means whereby four rectangular waveguides may be connected to a single waveguide having the form of a cross, means joining a second end of said fourth section to a first end of said fifth section, the sixth of said sections providing means whereby a waveguide in the form of a cross may be connected to a circular waveguide, means joining a second end of said fifth section to a first end of said sixth section and means joining a second end of said sixth section to said circular waveguide whereby electromagnetic energy may be transformed from the $TE_{0,1}$ mode in the rectangular guide to the $TE_{0,1}$ mode in the circular guide without exciting the dominant mode in said circular guide.

5. A mode transformer comprising six transition sections serially connected, said first transition section having a cross-sectional shape at a

first end thereof of a rectangular waveguide and having a shape at the second end thereof of two rectangular waveguides with a common broad wall, said second section having a shape at the first end thereof that is identical to the shape of said second end of said first section and having a shape at the second end thereof of two rectangular waveguides having a narrow wall in common, said third section having a shape at the first end thereof identical with the shape of said second end of said second section and having a shape at the second end thereof of four rectangular waveguides arranged in a square with two broad walls in common and two narrow walls in common, said fourth section having a shape at the first end thereof identical with said second end of said third section and having a shape at the second end thereof of four waveguides arranged in the form of a cross with one narrow wall of each waveguide forming the walls of a square at the center of said cross, said fifth section having a shape at the first end thereof identical in shape to said second end of said fourth section and having a shape at the second end in the form of a hollow cross, and said sixth section having shape at the first end thereof identical with the shape of said second end of said fifth section and having a shape at the second end thereof of a circle.
